DESIGN FOR A COMBINED BRUSH, COMB
AND HOLDER, OR THE LIKE

Albert H. Jung, Flushing, N. Y., assignor to Victor Metal Products Corporation, Brooklyn, N. Y., a corporation of New York

Application January 9, 1947, Serial No. 136,023

Term of patent 14 years

(Cl. D86—10)

To all whom it may concern:

Be it known that I, Albert H. Jung, a citizen of the United States and a resident of Flushing, city and State of New York, have invented a new, original, and ornamental Design for a Combined Brush, Comb and Holder, or the like, of which the following is a specification, reference being had to the accompanying drawing, forming part thereof, wherein:

Fig. 1 is a top plan view of a combined brush, comb and holder or the like, showing my new design.

Fig. 2 is a side elevational view thereof.

Fig. 3 is a front elevational view thereof.

Fig. 4 is a rear elevational view thereof.

I claim:

The ornamental design for a combined brush,

comb and holder, or the like, substantially as shown.

ALBERT H. JUNG.
